[57] CLAIM

The ornamental design for a writing implement with fins, as shown and described.

DESCRIPTION

FIG. 1 is perspective view of a writing implement with fins showing my new design;

FIG. 2 is a front elevation view thereof, all other sides being identical thereto;

FIG. 3 is a top plan view of the first embodiment of the design shown in FIG. 1 and 2;

FIG. 4 is a bottom plan view of the first embodiment of the design shown in FIGS. 1 and 2;

FIG. 5 is a front elevation view of a second embodiment of my new design, all other sides being identical thereto;

FIG. 6 is a top plan view of the second embodiment of the design shown in FIG. 5; and,

FIG. 7 is a bottom plan view of the second embodiment of the design shown in FIG. 5.
